DESIGN FOR A SODA STRAW DISPENSER

Elmer E. Mosley, Fort Worth, Tex.

Application December 29, 1945, Serial No. 125,213

Term of patent 14 years

(Cl. D52—2)

To all whom it may concern:

Be it known that I, Elmer E. Mosley, a citizen of the United States of America, residing at Fort Worth, in the county of Tarrant and State of Texas, have invented a new, original, and ornamental Design for a Soda Straw Dispenser, of which the following is a specification, reference being had to the accompanying drawing, forming part thereof.

I claim:

The ornamental design for a soda straw dispenser, substantially as shown.

ELMER E. MOSLEY.
